UNITED STATES PATENT OFFICE.

JOSEPH ALBERT HILL, OF SHEFFIELD, ENGLAND.

FURNACE-GRAVE FOR LOCOMOTIVE AND LIKE BOILERS AND OTHER PURPOSES.

1,212,058.

Specification of Letters Patent.

Patented Jan. 9, 1917.

Application filed March 12, 1912. Serial No. 683,199.

To all whom it may concern:

Be it known that I, JOSEPH ALBERT HILL, a subject of the King of Great Britain and Ireland, and resident of Bernard Road, 5 Park, Sheffield, in the county of York, England, have invented a certain new and useful Improved Furnace-Grate for Locomotive and like Boilers and other Purposes, of which the following is a specification.

10 This invention relates to furnace grates for locomotive and other boilers of the type composed of two or more portions adapted to be tilted about their longitudinal axes in such a manner as to leave one or more gaps 15 or slots through which the fire can be dropped thus obviating the usual tedious operation of dropping the fire-bars severally which leads to considerable delay in drawing the fire.

20 The object of the present invention is to devise an improved form of furnace grate of the above type in which the manipulation of the grate sections and of the bars composing the same shall be greatly simplified and 25 facilitated, and the invention consists in a furnace grate for locomotive and other boilers divided into two or more portions and provided with separate and independent gears enabling the fire-bars to be shaken 30 or the parts of the furnace grate to be rocked as a whole.

The invention also consists in adapting a single operating device to actuate both the shaking and rocking gears.

35 The invention further comprises the special form of furnace grate hereinafter more particularly described.

The accompanying drawings illustrate one mode of carrying out the invention.

40 Figure 1 is a longitudinal sectional elevation showing one convenient form of furnace grate constructed in accordance with the invention. Fig. 2 is a front elevation of a part of Fig. 1. Fig. 3 is a plan of a detail 45 of Fig. 2. Fig. 4 is a view illustrating the rocking of the furnace grate. Fig. 5 is a similar view illustrating the shaking of the fire-bars, while Fig. 6 is a plan on a somewhat larger scale showing a portion of the 50 rocking and shaking gears.

In carrying my invention into effect in one convenient manner when applying it, for example, to a furnace grate for locomotives of the type which is provided with a 55 plurality of longitudinally arranged air

conduits for facilitating the passage of air to the fuel and also for collecting the ashes for subsequent removal from the conduits by steam or like jets, the conduits *a* supporting transverse fire-bars *v* and of which there may be any convenient number (four such conduits being illustrated in the drawings) are rotatably mounted within the fire-box, for example, by means of plate or like members *u* which are secured to or formed 60 integral with pins *b* mounted in suitable bearings *c*, carried by the walls *d* of the fire-box.

The conduits are carried rotatably in the plates *u* in any suitable manner and for the 70 purpose of providing for both the rocking of the grate sections carried by the plates *u* and the shaking of the individual conduits and the bars carried thereby I provide two sets of rods *e* *f* connected in any suitable 75 manner with corresponding sets of bell crank levers *g* *h* pivotally mounted upon some fixed portion of the framing of the locomotive or of the fire-box and coupled together respectively by rods *i* *k* upon which 80 lugs or brackets *l* *m* are rigidly mounted.

The lugs *l* *m* are provided with slots adapted to be engaged when required by lugs or projections *n* carried by a lever *o* working in a guide plate *p* fixed in any convenient position in the cab of the locomotive. The guide plate *p*, as is more clearly shown in Fig. 3, is formed with a slot comprising two portions *q* *r* connected by a slot *s* at 85 right angles to the former. The arrangement is such that when the lever *o* is working in the slot *q* its lower end is in engagement with the lug or bracket *l* and consequently movement of the lever through the medium of the link *i* operates the bell crank 90 levers *g* and rods *e* so that the individual conduits, and with them the fire-bars, are tilted in the manner shown in Fig. 5, the oscillatory movement of the conduits being effected through the intermediary of the **T** 100 shaped or other suitable bars or connecting members *t* attached both to the conduits and to the rods *e*.

When the lever *o* is moved across the slot *s* its lower end is disengaged from the 105 bracket *l* and engages with the bracket *m* so that movement of the lever in the slot *r* operates the bell crank levers *h* and through them the rods *f* so that the brackets *u* are thereby tilted in the manner shown 110

in Fig. 4, the grate sections being rotated in opposite directions so that a gap is formed between them through which the charge upon the fire grate can be instantly tilted 5 into the ash-pit.

During the rocking action the shaking gear for the individual conduits is not in any way affected owing to the fact that the points at which the rods *e* are connected 10 with the bracket members *t* secured to the conduits are situated in or approximately in the axes of rotation of the pins *b* of the bracket members *u* and any slight movement that might be given to the rods due to slight 15 inaccuracy in the fitting of the apparatus can be eliminated by providing a slot at one end at each of the bars *e*.

If desired the grate may be formed in two halves, either of which may be adapted to 20 be tilted when required, or both may be separately tilted, separate operating mechanisms for the two halves of the grate being provided, if necessary, for this purpose. Such an arrangement allows of only one- 25 half of the fire being worked at a time, if desirable, the remaining part of the grate being thrown out of action by being tilted out of the horizontal.

A further advantage of the arrangement 30 is that the firemen may work the clean fire on to one-half of the grate and the clinker and ash on to the other half which may then be tilted for the purpose of getting rid of the waste after which this latter portion of 35 the grate may be returned to its normal position and the cleaned fire worked all over the grate area.

It will thus be seen that by means of my improved arrangement the furnace grate 40 can be thoroughly shaken during the running of the locomotive and the operations of rocking and shaking are capable of being readily performed by means of the one operating device.

45 It will be understood, however, that the actuating gear for the rocking and shaking of the furnace grate may be readily varied as required and also that separate operating

devices for actuating the rocking and shaking gear may be provided if desired.

Having now described my invention what I claim as new and desire to secure by Letters Patent is:—

1. A furnace grate for locomotive and other boilers and for other purposes comprising a plurality of sections comprising pivotally mounted fire-bars, link mechanism for effecting the tilting of said sections about their longitudinal axes, a second set of link mechanism for effecting the shaking of the fire-bars composing each section, a lever for operating either set of link mechanism as desired, and a guide plate having an angled slot for controlling the movements of the lever.

2. A furnace grate for locomotive and other boilers and for other purposes comprising two sections, each of which is composed of two conduits supporting transverse fire-bars therein, link mechanism for rocking the grate sections about their longitudinal axes, a second set of link mechanism for oscillating the individual conduits forming the sections, and a single operating member for actuating either set of link mechanism as desired.

3. A furnace grate for locomotive and other boilers and for other purposes comprising two sections, each of which is composed of two conduits supporting transverse fire-bars therein, link mechanism for rocking the grate sections about their longitudinal axes, a second set of link mechanism for oscillating the individual conduits forming the sections, a single lever for actuating either set of link mechanism as desired, and an angled guide controlling the movements of said lever.

In testimony whereof I have signed my name to this specification in the presence 90 of two subscribing witnesses.

JOSEPH ALBERT HILL.
